Filed July 9, 1970, Ser. No. 23,888

Term of patent 14 years

Int. Cl. D10—04

U.S. Cl. D52—6

FIG. 1 is a side elevational view of a meter readout unit embodying our new design;

FIG. 2 is a top plan view thereof;

FIG. 3 is a front elevational view thereof; and

FIG. 4 is a perspective view thereof.

The cable is broken away in the views to indicate indeterminate length and the broken line representation of a hose and nozzle in FIG. 1 is for purposes of illustration only.

We claim:

The ornamental design for a meter readout unit, as shown.
